VACUUM FUEL FEEDING APPARATUS

Filed Feb. 11, 1924

UNITED STATES PATENT OFFICE.

HENRY A. MILLER AND ROBERT H. RHOADES, OF NEW YORK, N. Y., ASSIGNEES TO
VACO MANUFACTURING CORPORATION, OF NEW YORK, N. Y., A CORPORATION OF
DELAWARE.

VACUUM FUEL-FEEDING APPARATUS.

Application filed February 11, 1924. Serial No. 692,085.

To all whom it may concern:

Be it known that we, HENRY A. MILLER and ROBERT H. RHOADES, citizens of the United States, residing at New York, in the county of New York and State of New York, have invented a certain new and useful Improvement in Vacuum Fuel-Feeding Apparatus, of which the following is a full, clear, and exact description.

10 This invention is in the nature of an improvement on the invention forming the subject of Patent No. 1,384,724 dated July 12th, 1921.

15 The object of the invention is to improve and simplify the construction and operation of the apparatus and measurably increase its efficiency.

20 In the patent, the invention is specifically shown as having the vacuum chamber and the liquid feeding chamber connected by a valvular by-pass located partly outside the apparatus, whereas in the present invention a substitute for the by-pass, in the form of a check valve, is placed between the inner 25 and outer chambers and concealed therein, thereby affording protection to the same, and decreasing the cost of the apparatus.

Again, in the patent the air valve attached 30 to the communicating tube on the diaphragm is made rigid, whereas in the present invention this valve rests on a spring weaker than the diaphragm.

Furthermore, in the patent, manufacturing practice has shown that the diaphragms 35 vary in resiliency, and the air valve construction in this present invention offsets such variation, and in addition keeps the air valve tightly closed when the diaphragm sags slightly before operating.

40 In the patent no provision has been made for obstructing the flow or splash of gasoline into and through the holes situated at the top of the communicating tube, excepting the form and arrangement of the 45 liquid inlet tube, whereas in the present invention we have placed a conically shaped baffle on the communicating tube below the holes therein to obstruct such flow or splash of gasoline. It is to be noted that this conically shaped baffle may be made of sufficient weight to materially effect and control the 50 operation of the diaphragm.

In the present invention to further pre-

vent the flow of gasoline in and through the holes in the communicating tube, that part 55 of the communicating tube containing the holes is housed in a tubular structure erected on the top of the apparatus.

In the patent the top cap sealing the apparatus is constructed in one piece, whereas 60 in the present improvement there is a cap to seal the inner chamber air tight and an additional cap to finish off and close the outer chamber.

In the patent the by-pass between the 65 vacuum chamber and the liquid feeding chamber is operated by gravity flow, whereas in the present improvement the check valve between the vacuum chamber and the liquid feeding chamber is operated by hydrostatic pressure rather than by gravity.

We show an alternative construction to 70 this hydrostatically controlled valve, with the valve arranged in a horizontal plane rather than a vertical plane.

In the accompanying drawings illustrating the invention, in the several figures of which like parts are similarly designated, Figure 1 is a longitudinal vertical section. Fig. 2 is a section showing the alternative 75 construction above referred to.

1 is the outer shell, preferably cylindrical, provided with a cap piece 2, and a base piece 3. 4 is an inner shell, preferably cylindrical, arranged within the outer shell, 80 and provided with a cap piece 5. The base piece 3 is provided with a head 6, bolted or otherwise secured to it in an air tight manner, and having in its joint the flexible diaphragm 7, of any suitable material and 85 design.

The cap piece 5 is hermetically sealed to the inner shell or cylinder 4, and it is provided with a nipple 8, by which the apparatus may be connected with a liquid supply, such as a gasoline tank, and it is also provided with an air inlet 9, which opens into the inner shell. The cap piece 2 is provided with a vent 10 which opens into the 90 space between the outer and inner shells.

100 The inner shell 4 forms the vacuum or receiving chamber 11, which is divided by the diaphragm 7 into upper and lower sections, and the space between the inner and outer cylinders forms the liquid feeding or delivery chamber 12.

The base 3, is provided with a liquid outlet 13, which may be connected with a carburetor.

The head 6 is provided with a nipple 14, which may be connected with an engine or other source of suction, and opposite this nipple is a communicating tube 15 connecting the upper and lower sections of the vacuum chamber 11 and fixed to and moving 10 with the diaphragm.

16 is a casting or other support suitably fixed to the shell 4 of the vacuum chamber 11 and having a check or flap valve 17, opening into the liquid feeding chamber 12, 15 that is to say, affording communication between the inner and outer chambers.

The tube 15 extends up into a cylindrical housing 18, mounted on the cap 5 and is therein provided with a needle valve 19, 20 resting on a spring 20 and cooperating with the air inlet 9.

The upper part of the tube 15, containing the needle valve 19, and spring 20 being housed in the housing 18, the needle valve 25 19 is guided into the air inlet 9. This needle valve serves to open and close said air inlet 9 as the diaphragm 7 moves downwardly and upwardly. To further stay, guide and retain the needle valve 19 it may be arranged in a cap 21 fastened to the upper end 30 of the tube 15.

The tube 15 at its upper end is provided with one or more lateral openings 22, and the housing 18 prevents splash from or flow 35 of the incoming liquid from entering said openings and as a further protection a flaring or conical baffle plate 23 is fixed to the communicating tube 15 at a suitable point under the lateral openings and preferably 40 adjacent to the opening of the liquid inlet 8 within the shell 4.

The working surface of the diaphragm may be relatively almost twice as great as the diameter of the inner shell 4.

45 The lowest part of the upper section of the vacuum chamber as well as all of the lower section are lower than the bottom of the liquid feeding chamber.

As shown in Fig. 2 the check valve or 50 flap valve 17 may be arranged in the base 3 instead of the shell 4, and any number of such valves may be used.

The feeding chamber 12 fills from the bottom, the liquid being forced into said chamber from the vacuum chamber through the check valve 17 by hydrostatic pressure, instead of flowing downward by gravity as in the patent referred to. When the suction is cut off and the vacuum chamber has 55 a column of liquid higher than the level of liquid in the feeding chamber, then by hydrostatic pressure the levels are equalized, or substantially so, by the flow of liquid through the valve 17, from the inner chamber 60 into the outer chamber. The outer 65

chamber holds a considerably greater weight of liquid than the inner, yet the valve 17 opens and the outflow from the inner chamber to the outer chamber starts when the height or level of liquid in the inner chamber is greater than the level of liquid in the outer chamber.

A flexible diaphragm may be replaced by any other suitable medium responsive to variations in weight or pressure in an apparatus of the character herein disclosed, but the purpose and object of the invention are best subserved when this movable medium is combined with a check valve and a feeding and delivery arrangement such as that disclosed, wherein a suction valve and an atmospheric valve are alternately opened and closed.

The tube 15 has in its upper end, a block 24 from which depends a rod 25 terminating in a needle valve 26 which works in the nipple 14 to open said nipple when the diaphragm is normal and to close it when the diaphragm is depressed, as in the patent referred to.

The operation will be understood from the foregoing, but it may be well to repeat and to do so in connection with a specific apparatus. To this end, let it be supposed that the apparatus is to be used in an automobile or other motor vehicle or motor apparatus using liquid fuel. The nipple 8 will be connected with the source of liquid supply, the nipple 14 will be connected with the engine, and the nipple 13 will be connected with the carburetor. Liquid fuel being admitted into the inner cylinder, will accumulate until the pressure forces the diaphragm 7 downwardly, closing the suction valve and opening the air valve, thus equalizing the atmospheric conditions in the inner and outer chambers, whereupon the pressure of liquid will force the check valve open and cause the liquid to rise into the outer chamber until the levels in both chambers are substantially equal.

The diaphragm 7, or its equivalent, being responsive to a vacuum, the pressure of the superposed liquid or the combination of both, will move so as to alternately open and close the air valve and suction valve.

The outer chamber is always open to the air through the air inlet 10.

It will be understood of course, that the tube 15 establishes constant communication above and below the diaphragm in the vacuum chamber, so that atmospheric or vacuum conditions existing in these two areas are alike or substantially alike.

What we claim is:—

1. A vacuum fuel feeding apparatus, comprising a liquid fuel receiving chamber, means to create a vacuum in said chamber and to break said vacuum, and a liquid fuel delivery chamber surrounding the receiving 120 125 130

- chamber, a valve arranged at the lower end of the receiving chamber and opening by hydrostatic pressure to establish communication between the two chambers, a liquid outlet from the delivery chamber, and a base on which these chambers are erected. 5. In a vacuum fuel feeding apparatus, a liquid feeding chamber and a liquid receiving chamber arranged within the former and communicating therewith, an air inlet for the liquid receiving chamber, a valve for opening and closing said inlet, a pressure responsive medium for operating said valve, and a spring acting against the valve and normally holding it closed against accidental movement of the pressure responsive medium. 55
2. A vacuum fuel feeding apparatus, comprising a liquid fuel receiving chamber, means to create a vacuum in said chamber 10 and to break said vacuum, and a liquid fuel delivery chamber surrounding the receiving chamber, a valve arranged at the lower end of the receiving chamber and opening by hydrostatic pressure to establish communication between the two chambers, a liquid outlet from the delivery chamber, an air tight cap for the receiving chamber and a separate cap for the delivery chamber, a liquid supply inlet, separate air inlets for 15 the respective chambers, a base on which the chambers are erected, and a head attached to the base and having means to connect with a suction producing apparatus. 60
3. A vacuum fuel feeding apparatus, having a vacuum chamber and a surrounding liquid feeding chamber, and a communicating element interposed between the two chambers, an air tight cap for the receiving chamber and a separate cap for the delivery chamber, a liquid supply inlet, separate air inlets for the two chambers, a base on which the chambers are erected, a head applied to 20 said base and forming part of the vacuum chamber, and an element arranged in said vacuum chamber and responsive to variations in pressure. 65
4. A vacuum fuel feeding apparatus, having a vacuum chamber and a surrounding liquid feeding chamber, a communicating element interposed between the two chambers, an air tight cap for the receiving chamber and a fitted cap for the delivery chamber, a liquid supply inlet, separate air inlets for the two chambers, a base on which 25 the chambers are erected, a head applied to said base and forming part of the vacuum chamber and having a suction connection, and a diaphragm supported in said vacuum chamber and provided with a tube opening 30 communication between the upper and lower sections of the vacuum chamber on opposite sides of the diaphragm and provided with means to control the air inlet and the suction connection of the vacuum chamber. 70
5. In a vacuum fuel feeding apparatus, a liquid feeding chamber and a liquid receiving chamber arranged within the former and communicating therewith, an air inlet for the liquid receiving chamber, a valve for opening and closing said inlet, a pressure responsive medium for operating said valve, and a spring acting against the valve and normally holding it closed against accidental movement of the pressure responsive medium. 75
6. In a vacuum fuel feeding apparatus, a liquid feeding chamber and a liquid receiving chamber arranged within the former and communicating therewith, an air inlet for the liquid receiving chamber, a valve for opening and closing said inlet, a carrier 70 for the valve responsive to variations in pressure in the chambers, and a separate spring support for said valve weaker than the carrier. 75
7. In a vacuum fuel feeding apparatus, a liquid feeding chamber and a liquid receiving chamber arranged within the former and communicating therewith, an air inlet for the liquid receiving chamber, a valve for opening and closing said inlet, a resilient diaphragm carrying the valve, and a separate spring support for the valve adapted to keep the valve tightly closed when the diaphragm sags slightly before operating. 80
8. In a vacuum fuel feeding apparatus, a liquid feeding chamber and a liquid receiving chamber arranged within the former and communicating therewith, a liquid inlet opening into said receiving chamber, a communicating tube arranged in said receiving chamber and provided near its upper end with lateral openings, and a baffle mounted on the tube below said openings. 90
9. A vacuum fuel feeding apparatus, comprising an outer delivery chamber, a receiving chamber arranged within and surrounded circumferentially by said outer chamber, the chambers being closed at their bottoms, the outer chamber having a top 100 closing cap and the inner chamber having a separate closing cap. 95

In testimony whereof we have hereunto set our hands this 5th day of February, A. D. 1924.

HENRY A. MILLER.
ROBERT H. RHOADES.
